INVENTOR

Alfred T. Bratton
WITNESS:

BY *Victor J. Evans*
ATTORNEY.

UNITED STATES PATENT OFFICE.

AARON M. ADAMS, OF PHILADELPHIA, PENNSYLVANIA.

CORD GRIPPING AND SECURING DEVICE.

Application filed June 11, 1920. Serial No. 388,295.

To all whom it may concern:

Be it known that I, AARON M. ADAMS, a citizen of the United States, residing at Philadelphia, in the county of Philadelphia and State of Pennsylvania, have invented 5 new and useful Improvements in Cord Gripping and Securing Devices, of which the following is a specification.

An object of the invention is to provide 10 a gripping and securing device for securing the ends of a cord or cords.

The invention is particularly adapted for use in connection with straw hats to secure the ends of certain cords of an elastic 15 nature and which are employed in connection with the sweat band of the hat to provide a cushioning or resilient portion therefor.

It will of course be understood that the 20 device may be generally employed in securing the ends of cords, ribbons or bands, but that I particularly desire it for use in connection with hats because of the effective manner in which it can be adapted to the 25 hat, concealed beneath the sweat band and made in a small compact form which will not in any manner affect the wearing of the hat.

In the further disclosure of the invention, 30 reference is to be had to the accompanying drawings constituting a part of this specification, in which similar characters of reference denote corresponding parts in all the views, and in which,—

Figure 1 is a perspective view of the member, and

Figure 2 is a view looking at the inner face of a sweat band of a hat which has been turned down to disclose the manner 40 of positioning the member.

Referring more particularly to the views the member, indicated in its entirety by the numeral 10 comprises a single piece of spring-like wire 11, which is bent to provide 45 a straight portion 12, with the ends bent upon themselves to form loops as at 13, the other straight portions 14 of which

are parallel to the straight portion 12, the ends being then bent away from the straight portion 12 and again bent upon themselves 50 to form larger loops 15 with the extremities 16 of the wire bent toward each other and engaging at the medial portion of the straight portion 12 and in fact having the ends or extremities 16 abutting against the 55 medial part of the straight portion 12. By the arrangement of the loops 15 and the abutting of the extremities of the wire against the straight portion, it will be apparent that the loops 13 will be of a spring-like nature and that the parts which form the loops 13 can readily receive the ends 60 of a cord 17 passing through the loops as shown. Particularly in a case of elastic cord, it will be clear that when a pull is 65 exerted on the end or ends which have been passed through the loops 13, that such pull will decrease the normal diameter of the cord so that it will readily slide through the loops and upon releasing the pull upon 70 the cord, it will tend to resume its normal diameter and thus be gripped or held in the loops 13 so that the band or loop formed by the cord in the sweat band 18 of a hat 19 can be subjected to a more or less tension by simply adjusting the device as to 75 the free ends of the cord.

Having described my invention, I claim—

As a new article of manufacture, a gripping and securing member comprising a 80 single piece of wire bent to form a straight portion and then having parts bent upon themselves to form auxiliary straight portions folded on the first mentioned straight portion and with said first mentioned straight portion forming gripping loops, the ends 85 of the wire being then bent outwardly and away from the first mentioned straight portion and bent upon themselves to have the extremities of the wire converge, meet and 90 abut against the first mentioned straight portion at the medial part thereof.

In testimony whereof I affix my signature.

AARON M. ADAMS.
